UNITED STATES PATENT OFFICE

2,433,975

VIBRATORY CONVEYOR MEANS FOR
IRONERS

William J. Asher, Colorado Springs, Colo.

Original application February 23, 1938, Serial No.
192,155. Divided and this application June 30,
1944, Serial No. 542,891

6 Claims. (Cl. 38—8)

1

This invention relates to ironing machines and particularly to ironing machines of the type utilizing, as one of the cooperating ironing elements, a travelling apron by means of which the goods undergoing ironing are held against a heated ironing surface.

In ironing machines of this type, and especially where the ironing surface is that of a rotating cylinder, articles of work frequently tend to cling to the apron and it is sometimes difficult to effect separation of the completed work from the surface of the apron after the apron has disengaged itself from the ironing surface. In ironing machines of the two cylinder type, involving the use of two cooperating aprons it is customary to effect the automatic transfer of goods which have been ironed on the first cylinder, to the second cylinder, by the coaction of the two aprons, these aprons being caused to travel in parallel paths with the goods between them to a point in the vicinity of the second cylinder, at which point the aprons are caused to diverge and the goods to drop from the apron of the first cylinder onto the apron of the second cylinder. At this point difficulties are frequently met owing to the fact that the goods to be again ironed on the second cylinder tend to cling to the apron of the first cylinder.

It is a primary purpose of the present invention to provide means for automatically dislodging goods which tend to cling to the travelling apron of an ironing machine and particularly to provide means suitable for dislodging goods either from a travelling apron which has just disengaged itself from an ironing cylinder, or which has cooperated with another apron in bringing goods to the vicinity of such cylinder from a distant point or, as in the case of the machine particularly contemplated by the invention, to dislodge goods from two aprons simultaneously, at the points mentioned.

The present application comprises a division of my co-pending application, Serial No. 192,155, filed February 23, 1938, which matured as United States Patent No. 2,394,421 on February 5, 1946, and much of the mechanism illustrated in the accompanying drawings is more particularly described in that application. Other somewhat related applications are Serial No. 542,890 and Serial No. 542,892, both filed concurrently herewith.

In the drawings:

Figure 1 is a side elevation of portion of an ironing machine of the apron and cylinder type to which machine the invention has been applied;

2

Figure 2 is an enlarged vertical section taken transversely through the shaft of the ironing cylinder, beyond the end of the cylinder, and showing the aprons and the apron guiding means;

Figure 3 is a section on line 3—3 of Figure 1;

Figure 4 is a section on line 4—4 of Figure 3; and

Figure 5 is a section on line 5—5 of Figure 3.

Portion of the frame of the ironing machine is indicated at 10 and, as shown in Figure 1, this portion supports for rotation about a horizontal axis an ironing cylinder, indicated at 11. The cylinder 11 shown comprises the second cylinder of a two-cylinder ironing machine, the first cylinder not being illustrated inasmuch as it comprises no portion of the present invention. The apron for the cylinder 11 is indicated at 12 and is endless, moving in the direction of the arrows A in Figure 2, a part of such apron being held in close contact with the surface of the cylinder 11 by the guiding and pressure rollers 13, 14, 15, 16, 17 and 18 illustrated and being further guided in its movement along a fixed endless path by rollers 20, 21, 22 and 23. The cylinder revolves in the direction of the arrow B and the work is passed onto the cylinder by the apron 12 as it moves around the pressure and guide roller 13, the ironing operation having been completed by the time the work reaches a position intermediate the cylinder and the guide and pressure roller 18.

Ordinarily, the work will cling to the cylinder surface and will be removed by doffing blades 24 mounted on doffing bar 25, and caused to pass onto a conveyor generally indicated at C and comprising a plurality of parallel spaced endless conveyor tapes 26 which pass around and over the doffing bar 25 and the tape driving and supporting roll 28, so that the pieces of work are successively passed outwardly in the direction of the arrow D and fall upon the delivery platform 29 from which platform they are removed by an operator. It sometimes happens, however, that goods tend to cling to the surface of the apron 12 and hence do not reach the doffing knives 24 and the tapes 26, passing instead outwardly and upwardly along the reach of the apron 12 extending from guide and pressure roller 18 to guide roller 22, and even around this idler and outwardly. To eliminate this possibility means is provided for vibrating that reach of the apron 12 which extends from the pressure and guide roller 18 to the guide roller 22, this straight reach being upwardly and outwardly inclined, in the machine illustrated; but being hereinafter described as a

generally horizontally extending reach, from the undersurface of which clinging ironed goods must be separated.

As previously stated there may be a second apron employed in an ironing machine of the type described, to cooperate in forwarding goods from a first cylinder to the second cylinder 11 to be again ironed and, in the machine illustrated in the drawings, such a second apron is indicated at 30, being guided in its movements, in the directions of arrows E by the guide and pressure rollers 15, 14 and 13, the guide roller 23, and the additional rollers 31, 32, 33, 34 and 35. As will be observed from an inspection of Figure 2 the aprons 12 and 30 are together while passing over rollers 15, 14, 13 and 23, but diverge or separate after passing around guide roller 23. It is desirable to provide means for causing the separation from the undersurface of that reach of the apron 30 which extends from the roller 23 to the roller 31, of goods which tend to cling, in order to cause all of such goods to fall downwardly upon the upper surface of the straight reach of the first apron 12 which is immediately below and to thereafter pass around the ironing cylinder 11 in the intended manner.

A simple mechanism for effecting the dislodgment of pieces of work clinging to the reach of the first apron which extends from guide and pressure roller 18 to guide roller 22, and from that reach of the second apron which extends from roller 23 to roller 31, is shown in the drawings, particularly in Figures 3, 4 and 5. It will be observed that the side members of the frame 10 are provided with bearings 10a, 10b for the ends of a rock-shaft or rocking bar 36 extending transversely of the machine and that there are fixed to this bar, as by welding, the free ends of the legs 37a of a generally U-shaped member 37. The intermediate or middle portion 37b of member 37 extends in a horizontal direction transversely of the machine and is located just above that reach of the second belt 30 which lies between the rollers 23 and 31. Part 37b of the U-shaped member 37 comprises a beater bar or rod which is raised intermittently during the operation of the machine and is allowed to fall by gravity so as to strike the underlying upper surface of the apron 30 and to thus vibrate the apron and cause goods clinging to its undersurface to be dislodged and to fall downwardly on the upper surface of the straight reach of apron 12 just below.

Slidably mounted on the parallel legs 37a of the U-shaped member 37 are bracket members 40 and these bracket members comprise supports for the ends of a second generally U-shaped member 41 the legs 41a of which are vertically disposed and the mid-portion 41b of which extends horizontally and is positioned just above the generally horizontal reach of apron 12, intermediate rollers 18 and 22. The brackets 40 may be adjusted longitudinally along the parallel legs 37a of member 37 and by moving the U-shaped member 41 toward or away from the rocking bar 36 the relative positions of the beater bars 37b and 41b may be so established that, if these bars are simultaneously raised and then allowed to fall, they will simultaneously contact the upper surfaces of those reaches of the respective aprons from which they are intended to dislodge clinging pieces of work.

The means for effecting the oscillation of the shaft or bar 36 and the oscillatory movements of the beater rods 37b and 41b is shown particularly in Figures 3, 4, and 5 and is seen to comprise

essentially a cam device R mounted upon a shaft 42 the ends of which shaft are suitably supported in bearings 10c and 10d formed in the side frame members of the machine. Shaft 42 preferably 5 also supports guide roller 23 which supports and is driven by an apron of the machine, or the necks of roll 23 may be mounted in bearings 10c and 10d, the shaft being dispensed with. Alternatively, the cam device R may be revolved by gearing 10 which is in turn connected to the driving means of the machine, so as to be revolved at the desired angular rate. Fixed upon the shaft is a member 44 having four arms 44a each having a cam surface 44b. As the member 44 revolves the cam surfaces of the several arms successively contact with the end of an arm 45 fixed upon the rocking bar 36, each cam making such contact effecting elevation of the end of arm 45, rocking of the shaft 36, and elevation of the beater rods 37b and 41b. As 15 soon as the arm 44a which has been active disengages the end of arm 45 the arm permits the beater rods 37b and 41b to fall and these rods will freely fall until they come into contact respectively with the upper surfaces of the aprons 12 and 30, 20 in the manner previously described. Such contact jars loose from the undersurface of the aprons any piece of work which might be clinging thereto. If the cam device is driven by an apron-engaging and guiding roller its speed of revolution 25 will vary with the speed of linear travel of the apron and hence the vibratory movements of the beater rods 37b and 41b will be increased as the apron speed is increased and will be decreased as the apron speed decreases. If the cam device 30 is separately driven the rapidity of operation of the beating rods may be varied as desired.

The novel apron vibrating mechanism may be applied to ironing machines of the chest type, as well as to ironing machines of the rotating 35 cylinder type, the problems involved in clearing the aprons being substantially the same in both cases.

Having thus described the invention, what is 40 claimed as new and desired to be secured by Letters Patent is:

1. In an ironing machine, in combination, a member having an ironing cylinder, an endless apron, guide means for said apron whereby it is caused to move along a first substantially horizontal reach as it approaches the cylinder and to move along a second substantially horizontal reach after leaving the cylinder, a second apron for cooperating with the first apron in the transmission of work to said cylinder, said second apron having one reach overlying and spaced from the second reach of the first apron and mechanism for vibrating the second reach of the first apron and the aforementioned reach of the second apron to dislodge any work tending to cling to the undersurfaces thereof.

2. The combination set forth in claim 1 in which said mechanism comprises a bar mounted on the machine for oscillation, means for oscillating said bar, and beater rods supported on said bar for oscillation therewith, and disposed adjacent said reaches for striking said aprons at one point in their paths of oscillation.

3. The combination set forth in claim 1 in which said mechanism comprises a bar mounted on the machine for oscillation, a U-shaped beater rod mounted at its ends on said bar, a second U-shaped beater rod bridging the legs of the first-named U-shaped rod, the cross-members of 50 the respective U-shaped rods disposed adjacent

said reaches for intermittently striking said aprons, and means for oscillating said bar and rods.

4. In an ironing machine, in combination, a rotating ironing cylinder, an apron adapted to move for a portion of its travel around the cylinder to cause the work to closely contact the cylinder, means guiding the apron along a generally horizontal reach in proximity to the cylinder, and mechanism for dislodging articles from the undersurface of said apron while moving along said reach, such mechanism including a beater rod positioned above said reach and means for lifting the rod periodically and permitting the same to fall upon the apron from above.

5. An ironing machine comprising, in combination, an ironing surface, means for effecting the movement of work through the machine one or more traveling work-confining aprons cooperating with said means to maintain the work in contact with said work moving means, guiding means for said apron leading it to assume a straight line reach with its work-engaging surface turned downwardly for a portion of its travel adjacent one or more points where the restraint on the work is to be relaxed as when the work is to be transferred from one part of the work moving means to another, and means for vibrating said apron at such reaches in order to prevent articles of work clinging to the confining apron instead of following a work moving means.

6. An ironing machine comprising, in combination, an ironing surface, means for effecting the movement of work through the machine, one or

more travelling work-confining aprons cooperating with said means to maintain the work in contact with said work moving means, guiding means for said apron leading it to assume a substantial horizontal straight line reach with its work-engaging surface turned downwardly for a portion of its travel adjacent one or more points where the restraint on the work is to be relaxed as when the work is to be transferred from one part of the work moving means to another, and means for vibrating said apron at such reaches in order to prevent articles of work clinging to the confining apron instead of following a work moving means, said means comprising a horizontally disposed striking bar arranged above said reach and means for intermittently causing said bar to strike the apron from above.
